POWDER-COMPRESSING MACHINES

Kenneth Brierley, 104 Wilbury Road, Letchworth, Hertfordshire, England

Filed July 3, 1957, Ser. No. 669,869

2 Claims. (Cl. 141—74)

This invention relates to dispensers for powdered, granular and like materials, and more particularly to such dispensers having agitator means, its object being to provide an improved construction wherein the agitator means are caused to enter a receptacle to which the material is dispensed, thereby to ensure even filling of the receptacle with the material, and the elimination of air spaces therein.

According to the present invention, a dispenser for powdered, granular and like materials comprises a supply pipe or hopper, means for positioning a receptacle below an outlet thereof to receive material, and an agitator capable of being moved into and withdrawn from the receptacle so as to permit agitation of the material while in the receptacle. Advantageously the agitator is arranged to be positioned wholly within the supply pipe or hopper when not engaged into the receptacle.

The means for positioning a receptacle below the hopper may comprise a movable platform having a number of chambers which are brought in turn opposite the outlet of the supply pipe or hopper, the platform being a close sliding fit against the outlet so as to seal the outlet between the movement away of one chamber and the movement into position of another chamber.

Preferably the agitator is capable of rotation in the supply pipe or hopper, for agitation purposes, and also of axial sliding for the purpose of moving into and out of the receptacle. By way of example, the agitator may be provided with clutch means so as to be caused to rotate only when moved into position within the receptacle. The agitator may conveniently be sprung urged into the receptacle.

In order that the nature of the invention may be more readily understood, an embodiment of hopper and agitator in accordance therewith is hereinafter particularly described with reference to the accompanying drawing, which is a central vertical section.

In this drawing, a machine frame 1 supports a stationary column 2 serving as a mounting for two bushings 3, 4. The two bushings are arranged one at each end of a rotatable tube 5 and two horizontal support arms 6, 7 are secured one at each end of the tube, the arms being capable of swinging round in a horizontal plane. The lower arm 6 is apertured at its other end to serve as a seating for the lower narrower end of a conical hopper 8 the lower end of which is flush with the lower surface of the arm 6. The upper arm 7 is apertured at its other end to receive a bearing sleeve 9 in which is rotatable and axially slideable a shaft 10 carrying at its lower part three agitator fingers 11, 12, 13. The shaft 10 is urged upwardly by a compression spring 9a acting between a fixed bushing 9b and a clutch plate 9c abutting axially against another clutch plate 9d carried on a shaft 14 mounted in bearing 15 and keyed to receive rotary drive from a pulley 16 disposed in a gap in a bearing block 17 supported on the upper arm 7. The upper end 14 of shaft 10 has a double flange device 18 in the channel of which is arranged a pin 19 secured at one end of a

2

lever 20 pivoted on a bracket 21 on the mounting 17, the other end of the lever 20 being coupled to a wire 22 forming the "inner" of a flexible control cable of the well-known kind commonly known as "Bowden" cable. An 5 "outer" sheath 23 for the cable is seated in a shouldered bore in the upper arm 7. The inner wire 22 of the cable is connected to any suitable device (not shown) capable of imparting to it a reciprocating motion of suitable amplitude; this could be provided for example by 10 a simple edge-cam driven at suitable speed from a main drive shaft for the machine. It will be apparent that as the inner wire 22 is reciprocated, the shaft 14 will be moved up and down within limits, and each time the shaft 14 is lowered it engages the clutch 9d, 9c and 15 depresses the shaft 10 against its spring 9a, thereby moving the fingers 11, 12, 13 from their upper position, shown in broken line, to their lower position as illustrated in full line. In the upper position the bottom ends of the fingers 11, 12, 13 are raised just within the lower 20 end of the hopper 8. In the lowered position they protrude a short distance below the open end of the hopper. Immediately below the lower arm 6 is positioned a rotatable platform or table 24, the rotation of which brings, step by step, each one of a series of chambers 25 into 25 line with the lower end opening of the hopper 8. The platform is driven by any suitable intermittent drive means (not shown) the construction and operation of which will be obvious to those skilled in the art of mechanical driving devices and which need not be described 30 in detail. The timing of the apparatus as a whole is such that each time a chamber 25 comes into position below the hopper 8, the wire 22 is slackened to allow a compression spring 26, acting between a bracket 27 on the mounting 17 and the lever 20, to push the pin 19 35 downwardly and lower the shafts 14, so that the clutch is engaged and the fingers 11, 12, 13 pass down into the lowered position shown in full line, in which position they are within the aperture 25. The fingers 11, 12, 13 constitute together an agitator which is driven in rotation by 40 a belt 28 engaged on the pulley 16 and on a driving pulley 29 secured at the upper end of an inner driving shaft 30 carried by a bearing 31 in the column 2. Any suitable driving unit (not shown) is coupled to the lower end of the shaft 30 for continuous rotation at relatively slow speed.

The device shown is part of an apparatus for the compression of cosmetic powder into shallow metal containers, the operation being as follows. In the chamber 45 25 is arranged a vertically slideable compression plunger 32 moved upwardly, at predetermined intervals, by a high pressure hydraulic ram device (not shown) connected to its stem 33 and situated generally below the frame 1 and table 24. As the table 24 revolves in a step-by-step motion, a shallow metal receptacle 34 is inserted into the chamber 25 by hand or by any suitable automatic dispenser, and is seated on the plunger 32. When the chamber comes into position below the hopper, loose powdered material in the hopper 8 falls by gravity into the upper part of the chamber 25 and onto the receptacle 50 34. At the same time the agitator fingers 11, 12, 13, descend into their lowered position and stir the powdered material within the chamber 25 itself, thereby ensuring that the powdered material completely fills the chamber, that its consistency is substantially homogeneous, and that no air spaces are inadvertently left in the powder contained in the aperture 25. After a short period of such filling and stirring, the agitator fingers 11, 12, 13 are raised again, by pulling operation of the wire 22, moving the shaft 14 upwardly and releasing the clutch, where- 55 60 65 70 after the rotatable platform or table 24 moves a further portion of a turn to bring the filled chamber 25 beneath a pressure stop (not shown), in which position the

plunger 32 is forced upwardly to compress the powdered material against the pressure stop and mould it into the form of a shallow cake in the receptacle 34. The platform 24 is a close sliding fit beneath the hopper 8 and thus closes the latter off during rotation, preventing powdered material from escaping until such time as the next chamber 25 comes into position below the hopper.

I claim:

1. In a machine for compressing measured quantities of cosmetic powder into a cake, a machine frame, a gravity feed hopper thereon to contain a bulk supply of the powder in freely flowing state, said hopper having an outlet opening at its lower end, a platform mounted on the frame and slidably movable across the outlet opening of the hopper and having portions of its upper surface serving as a closure for said opening, said platform having a plurality of chambers opening at its upper face between said portions to receive receptacles to be filled, said chambers being positioned so as to be brought selectively into alignment with the hopper outlet thereby to cause the selected chamber to be gravity-filled with powder from the hopper, a plurality of agitator fingers, and means mounting said fingers on the frame so as to be spaced radially from and rotatable about an axis coincident with the axis of the selected chamber and so as to be movable vertically between a raised and inoperative position in which they lie within the hopper above the upper surface of the platform, and a lowered and operative position in which they lie within and describe circles within the powder contained in the selected chamber, for the purpose of agitating and stirring said powder while the chamber is still in free communication with the bulk supply in the hopper.

2. In a machine for compressing measured quantities of cosmetic powder into a cake, a machine frame, a

5 gravity feed hopper thereon to contain a bulk supply of the powder in freely flowing state, said hopper having an outlet opening at its lower end, a platform mounted on the frame and slidably movable across the outlet opening of the hopper and having portions of its upper surface serving as a closure for said opening, said platform having a plurality of chambers opening at its upper surface between said portions to receive receptacles to be filled, said chambers being positioned so as to be brought selectively into alignment with the hopper outlet thereby to cause the selected chamber to be gravity-filled with powder from the hopper, a plurality of agitator fingers, means mounting said fingers on the machine frame above the hopper so as to be spaced radially from and rotatable about an axis coincident with the axis of the selected chamber, and so as to be vertically shiftable, said fingers depending through the entire height of the hopper and being of such length that their lower ends are movable between a raised inoperative position in which said ends lie within the hopper above the upper surface of the platform, and a lowered and operative position in which said ends lie within and describe circles within the powder contained in the selected chamber, whereby the contents of the hopper are agitated and the powder contained in the selected chamber is also agitated while the chamber is in free communication with the bulk supply in the hopper.
